UNITED STATES PATENT OFFICE

149,617

DESIGN FOR A CONTAINER CLOSURE OR SIMILAR ARTICLE

Maxwell H. Conman, New Kensington, Pa.

Application February 9, 1946, Serial No. 126,408

Term of patent 7 years

(Cl. D58—26)

To all whom it may concern:

Be it known that I, Maxwell H. Conman, a citizen of the United States, residing at New Kensington, in the county of Westmoreland and State of Pennsylvania, have invented a new, original, and ornamental Design for a Container Closure or Similar Article, of which the following is a specification, reference being had to the accompanying drawing, forming part thereof.

The figure is a perspective view of a container closure or similar article, embodying my new design.

I claim:

The ornamental design for a container closure or similar article, as shown.

MAXWELL H. CONMAN.
